UNITED STATES PATENT OFFICE.

JOHN B. LEIGHTON, OF BROCKTON, MASSACHUSETTS.

CHECKREIN-GUIDE.

SPECIFICATION forming part of Letters Patent No. 663,125, dated December 4, 1900.

Application filed June 2, 1900. Serial No. 18,798. (No model.)

To all whom it may concern:

Be it known that I, JOHN B. LEIGHTON, of Brockton, county of Plymouth, State of Massachusetts, have invented an Improvement in 5 Checkrein-Guides, of which the following description, in connection with the accompanying drawings, is a specification, like characters on the drawings representing like parts.

This invention relates to checkrein-guides; 10 and the object of the invention is to provide a simple and inexpensive device of this character which can be quickly and readily attached to or detached from a bridle or other part of a harness, the guide being so mounted 15 that it can freely turn as the horse turns his head, thereby preventing the rein from chafing or wearing against the loop or loops constituting a part of the guide.

One of the features of the invention consists 20 in the combination, with a bridle, of a guide connected to one of its straps for turning movement, said guide having means to receive and retain a checkrein, and in the present instance such guide consists, preferably, of a 25 plurality of open loops through which the straps of the checkrein can be readily passed without the necessity of threading the same therethrough, the latter being the usual custom.

30 In the drawings the checkrein-guide is represented as comprising a body having checkrein-loops and provided intermediate said loops with a transverse shank adapted to be suitably connected with a bridle. A convenient manner is by forming a pivot-opening in said shank to receive the tongue of the buckle to which the winker-stay is connected.

In the drawings, Figure 1 is a perspective view of a bridle of ordinary kind, showing my 40 checkrein-guide in connection therewith. Fig. 2 is a plan view of a portion of the bridle and the guide, both on an enlarged scale; and Fig. 3 is a perspective view, also on an enlarged scale, of the guide detached.

45 I have designated the bridle shown in part in Figs. 1 and 2 by A, it having the usual crown-piece 5, provided upon its upper side with a winker-stay buckle, as 6, extending forward therefrom to receive the winker stay or 50 strap 7.

The loops ordinarily employed to receive checkreins have no side motion, so that when

the horse turns his head the branches of the rein are caused to bind against the outer or inner sides of the loops, as the case may be, 55 thereby wearing them away and also exerting such a leverage upon said loops that they are soon stripped from the crown-piece. My improved checkrein-guide, however, is mounted to turn, so that these disadvantageous features are wholly avoided

The checkrein-guide (see Fig. 3) is denoted in a general way by B, and it comprises a body having loops at its ends shown as resilient tongues 9 and 10, said loops being opposite one another, and a shank or stem 12, extending forward from the latter. Said tongues with the adjacent portion of the body form open loops to receive the straps of the checkrein. Said shank or stem is in the 70 present instance connected with the winker-stay buckle 6, and its forward end is curved downward and has an opening 14 to receive the tongue 15 of the buckle 6, as indicated in Fig. 2. Just back of the buckle 6 the usual 75 loop 16 is arranged, its purpose being to receive the free end of the stay or strap 7 after the tongue is passed through one of the holes of the same. This loop 16 is also adapted to receive the shank 12 when the checkrein-guide 80 B is being applied. To connect said checkrein-guide with the bridle, the forward end of the shank 12 is passed forward through the loop 16 until the opening 14 is in position to receive the tongue 15, and the latter being 85 slightly elevated to bring it into line with the opening the guide B will be drawn back until the curved portion 13 thereof strikes against the short strap 17, connecting the buckle 6 with the crown-piece A. After this is done 90 the winker-stay is connected with its buckle. The tongue 15 serves as an effective pivot for the guide B and allows the same to readily turn back and forth. The tongues 9 and 10 are integral with the guide, the part B being 95 conveniently formed in one piece and being cheaply produced by stamping from sheet metal. The tongues 9 and 10 are resilient, so that the free portions thereof can be raised to freely insert and remove the branches or straps of the checkrein to save time in hitching up a horse, as ordinarily this is done by threading the branches of the checkrein through their guide-loops. The free ends of 100

the tongues are **U**-shaped, as at 18, the under rounded sides of which are contiguous to the upper face of the body 8, and, being rounded, they cannot cut the rein. The outer branches 5 of the two **U**-shaped portions also present inclined surfaces against which the branches of the checkrein can be forced, so as to more easily raise said tongues to apply the rein.

Having described my invention, what I 10 claim, and desire to secure by Letters Patent, is—

A checkrein-guide comprising a body having checkrein-loops, and provided between

said loops with a transverse shank, the forward end of said shank being curved downward, and said curved end having an opening to receive the tongue of a buckle or other pivot.

In testimony whereof I have signed my name to this specification in the presence of 20 two subscribing witnesses.

JOHN B. LEIGHTON.
